UNITED STATES PATENT OFFICE

STEVE NAGY, OF WOODBRIDGE, NEW JERSEY

JOINT CHAIR AND RAIL LOCK

Application filed August 22, 1930. Serial No. 477,079.

This invention relates to certain new and useful improvements in joint chairs and rail locks.

The primary object of the invention is to provide a rail joint chair and rail lock in which the meeting ends of rails are seated in a chair with a lock construction associated with the rail ends for holding them locked in the chair.

10 A further object of the invention is to provide a joint chair and lock of the foregoing character wherein the lock device is placeable as a unit in locking engagement with staples or bolt keepers carried by the rail ends 15 for holding the latter in assembled relation, the lock being constructed in a manner whereby movement of a controlling arm in the mechanism thereof may be shifted relative to the lock casing for holding the locking pins 20 or bolts against movement when engaged with the keepers on the rail ends.

With the above and other objects in view that will become apparent as the nature of the invention is better understood, the same 25 consists in the novel form, combination and arrangement of parts hereinafter more fully described, shown in the accompanying drawings and claimed.

In the drawings:—

30 Figure 1 is a top plan view of a rail joint chair and lock associated therewith;

Figure 2 is a side elevational view of the same;

35 Figure 3 is a side elevational view with one hinged section of the joint chair moved to open position and illustrating the lock mechanism engaged with keepers passing through meeting ends of the rails;

40 Figure 4 is a fragmentary side elevational view of the other side of the joint chair;

Figure 5 is a side elevational view, similar to Figure 3 showing the lock mechanism in depressed position, and disengaged from the keepers passing through the rail ends;

45 Figure 6 is a fragmentary side elevational view showing the keepers on one side of the joint chair and the openings in the rail ends through which the keepers pass;

50 Figure 7 is a cross-sectional view taken on line 7—7 of Figure 2; and

Figure 8 is a cross-sectional view taken on line 8—8 of Figure 2.

Referring more in detail to the accompanying drawings, the reference numerals 10 designate the meeting ends of rails, each 15 of which has a slotted opening 11 in the web portion thereof as shown in Figure 6, each rail end as shown in Figure 8 also having an opening 12 therein inwardly of the slotted opening 11 for purposes presently to appear. 60

The meeting rail ends are adapted for seating in a joint chair comprising a base plate 13 upon which the rail ends are seated and a pair of hinged side walls 14 and 15 hinged to opposite side edges thereof as at 16, the side walls 14 and 15 performing the functions of fish plates or splice bars. A pin 17 projects laterally from the side face of the side wall 14 at a point adjacent each end thereof for passage through the openings 12 in the rail ends as shown in Figure 8, the upper edge of the side wall 15 being notched as at 18 providing clearances for the pins 17 when the side walls 14 and 15 are in assembled relation 65 relative to the meeting rail ends as shown in Figures 7 and 8. Each pin 17 projects outwardly of the side wall 15 and in its projecting end is provided with a transverse opening 19, a retaining rod 20 being positioned in said openings outwardly of the side wall 15 70 for retaining the latter in closed position, the rod 20 passing beneath overhanging flanges 15a at each end of the side wall 15 as illustrated to aid in retaining the rod in position. 75

80 A pair of staples or lock bolt keepers 21 project laterally from the inner faces of the side wall 14 of the joint chair adjacent the pins 17 and extend through the slotted openings 11 in the meeting rail ends to project into a pocket or compartment 22 formed on the 85 inner face of the side wall 15 intermediate its ends. 90

The lock mechanism for retaining the rail ends in assembled relation in the joint chair is set into the compartment 22 and comprises 95 an open sided casing having one side wall 23, end walls 24, a bottom wall 25 and a top wall 26, the closed side wall 23 of the lock casing being placed in engagement with the webs of the meeting rail ends and having openings 100

27 therein registering with the openings 11 in the rail webs, the bolt keepers 21 extending through the registering openings 11 and 27 as shown in Figs. 3 and 5.

5 The lock mechanism comprises a vertically 10 slidable tensioned plate 28 having pairs of lugs 29 and 30 projecting from the upper and lower edges thereof that are slidably mounted upon guide pins extending between the bottom and top walls 25 and 26 of the lock 15 casing, the lower ends 31 of the guide pins being of increased diameter relative to the upper ends 32, while a coil spring 33 surrounds each guide pin between the lug 29 and the upper end of the lower enlargement 31 for tensioning the plate 28 in an upward direction. Each end of the sliding plate 28 carries a lock bolt 34 to be engaged by the adjacent keeper 21. A center lug 35 carried 20 by the plate 28 supports a perpendicular pin 36 which carries at its upper end a hollow push button 37 moving into guideways 38 formed in the side portions of the treads of the rail ends as illustrated. A lever for controlling 25 operation of the sliding plate 28 and shown at 39 is pivotally mounted as at 40 upon the plate 28 with a finger 41 upon its lower end adapted to be moved into alignment with the opening 42 in the bottom wall 25 of the lock case, the upper end of the lever 39 being 30 bifurcated as at 43 so that an implement or key inserted through the opening 44 in the hollow push button 37 is positioned between the furcations 43 of the lever for moving the same upon its pivot 40 to displace finger 41 laterally of the opening 42 for engagement with the bottom wall 25 of the lock case as shown in Figure 3 to hold the sliding plate 28 against movement. The lever 39 is retained 35 in its adjusted position against movement by the leaf spring 45 guided at its ends upon the pins 31 and engaged intermediate its ends by the lug 46 upon the finger 41.

From the above detailed description of the 40 invention, it is believed that the construction and operation thereof will at once be apparent, it being noted that the rail ends are moved laterally into position on the bottom wall 13 of the joint chair with the pins 17 and keepers 45 21 carried by the side wall 14 of the chair movable through the openings 11 and 12 in the rail ends. The lock mechanism is then disposed in engagement with the sides of the rail webs by first depressing the plunger button 37 so that upon release thereof the bolts 34 move into engagement with the keepers 21. The lever 39 is then moved upon its pivot 40 to hold the sliding plate and lock bolts against movement. Upon closing the side wall 15 of the joint chair, the pins 17 pass through the cut away portions 18 and the locking rod 20 is inserted through the openings 19 in the projecting ends of the pins 17.

While there are herein shown and described 65 the preferred embodiments of the invention,

it is nevertheless to be understood that minor changes may be made therein without departing from the spirit of the invention or the scope of the subjoined claims.

I claim:

1. In a rail joint chair and lock, the combination with meeting rail ends carrying lateral lock bolt keepers, of a lock device engaged with the keepers, and a joint chair inclosing the lock device. 70

2. In a rail joint chair and lock, the combination with meeting rail ends carrying lateral lock bolt keepers, of a lock device engaged with the keepers, a joint chair inclosing the lock device, and said lock device being bodily removable from the chair. 75

3. In a rail joint of the character described, meeting rail ends having openings in the webs thereof, a joint chair having hinged side walls, laterally directed pins and keepers carried by one wall extending through the openings in the rail webs, a lock device engaged with the keepers, and said pins extending through the other wall of the chair and anchored outwardly thereof. 80

4. In a rail joint of the character described, meeting rail ends having openings in the webs thereof, a joint chair having hinged side walls, laterally directed pins and keepers carried by one wall extending through the openings in the rail webs, a lock device engaged with the keepers, and said pins extending through the other wall of the chair and anchored outwardly thereof, said lock device including a tensioned sliding plate carrying lock bolts engageable with the keepers and retained in position by the keepers. 85

5. In a rail joint of the character described, meeting rail ends having openings in the webs thereof, a joint chair having hinged side walls, laterally directed pins and keepers carried by one wall extending through the openings in the rail webs, a lock device engaged with the keepers, said pins extending through the other wall of the chair and anchored outwardly thereof, said lock device including a tensioned sliding plate carrying lock bolts engageable with the keepers and retained in position by the keepers, and means for holding the sliding plate against movement when the bolts are engaged with the keepers. 90

6. In a rail joint of the character described, meeting rail ends having openings in the webs thereof, a joint chair having hinged side walls, laterally directed pins and keepers carried by one wall extending through the openings in the rail webs, a lock device engaged with the keepers, and said pins extending through the other wall of the chair and anchored outwardly thereof, said lock device including a tensioned sliding plate carrying lock bolts engageable with the keepers and retained in position by the keepers, a lever pivoted on the plate and operable 95

for holding the plate against sliding movement.

7. In a rail joint of the character described, meeting rail ends having openings in the webs thereof, a joint chair having hinged side walls, laterally directed pins and keepers carried by one wall extending through the openings in the rail webs, a lock device engaged with the keepers, said pins extending through the other wall of the chair and anchored outwardly thereof, said lock device including a tensioned sliding plate carrying lock bolts engageable with the keepers and retained in position by the keepers, a lever pivoted on the plate and operable for holding the plate against sliding movement, and a plunger button for operating the sliding plate set into cut-outs formed in the ends of the rail treads.

20 In testimony whereof I affix my signature.
STEVE NAGY.
